BUCKLE

Rudolph E. Schreiber, Chicago, Ill.

Application May 3, 1943, Serial No. 485,543

3 Claims. (Cl. 24—186)

The invention relates to improvements in buckles and more particularly to a plastic buckle having novel means to be engaged by a hook element in a manner to prevent transverse shifting of said hook.

Most known types of buckles usually are made of metal and have movable tongues hingedly connected to a cross-bar for engaging in openings in one end of an associated strip when the latter is threaded therethrough. In use, such buckles are attached, either permanently or demountably, by means of the cross-bar to the other end of said strip. In the event of a demountable attachment, the said other or attached end of the strip carries a suitable hook element arranged to engage over the cross-bar. Obviously, any shifting of the hook element transversely on the bar results in an untidy appearance in the strip and buckle when finally assembled, due to misalignment of the overlapping edges.

Known types of buckles having movable cross-bars with integral or attached tongues present difficult manufacturing problems when made of plastics, shaped bone, wood, fiber or other strong form retaining material, primarily because of the difficulties encountered in joining the pre-formed parts.

It is, therefore, an object of the present invention to provide a one-piece buckle with a rigid tongue and cross-bar wherein the latter is particularly suited to be engaged by a hook element and prevent shifting of the hook transversely.

Another object is to provide the cross-bar of a buckle with novel means to prevent transverse shifting of an associated hook element.

Another object is to provide a buckle with a novelly mounted tongue-carrying cross-bar.

Another object is to provide a resiliently flexible buckle with deformable journals to facilitate mounting of a rotatable cross-bar.

The foregoing and such other objects of the invention as will appear hereinafter as the description proceeds will be more readily understood from a perusal of the following specification; in which reference is had to the accompanying drawing; wherein

Fig. 1 is a fragmentary elevational view of a belt having one embodiment of the improved buckle associated therewith.

Fig. 2 is a front elevational view of the buckle shown in Fig. 1, attached to one end of the belt.

Fig. 3 is a rear elevational view of the buckle shown in Fig. 2.

Fig. 4 is a horizontal sectional view taken on

line 4—4 of Fig. 2, showing the belt threaded into place.

Fig. 5 is a rear elevational view of a modified form of buckle.

Fig. 6 is an end elevational view of the cross-bar journal, as viewed substantially along line 6—6 of Fig. 5.

Fig. 7 is a view similar to Fig. 6, showing the cross-bar positioned for insertion into the journal.

The buckle illustrated in Figs. 1 to 4, inclusive, may consist of a substantially rectangular frame having transverse end portions 11 and 12 and connected longitudinal side portions 13 and 14. Side portions 13 and 14 may be bowed longitudinally in the manner of conventional buckles, as best illustrated in Fig. 4, thereby disposing its end portions 11 and 12 rearwardly of the plane of its medial portion. The opening within the buckle frame, generally indicated at 15, is bisected by a transverse cross-bar 16 which, as shown, is integral at its ends with the respective side portions 13 and 14 and preferably is disposed rearwardly of the plane of the front frame.

The transverse cross-bar 16 has an integral tongue 17 which extends from one side substantially at right angles thereto longitudinally of the buckle frame and substantially midway between the side portions 13 and 14. The tongue 17 preferably is of greater length than, and completely bridges the portion of the opening 15 between the cross-bar 16 and the respective end portion 12 of the frame. As shown, the free end of the tongue necessarily is partially disposed out of the plane of the frame end portion 12 and has its free terminal spaced forwardly of but slightly overlapping the front face of said frame end. The gap 18 between the free terminal of the tongue and the frame end portion 12 preferably is sufficiently wide to permit threading of the free end 19 of the associated belt therethrough. It may be desirable to suitably recess or notch that portion of the frame end 12 immediately adjacent the tongue terminal, as at 21, to increase the effective width of the gap 18 so as to accommodate belts having eyelets in the openings therein.

The other end 22 of the belt may be fixedly secured to the cross-bar 16 but in this instance it carries a hook element 23 having spaced apart hook portions 24 arranged to engage over the cross-bar 16. This form of organization frequently is desirable in instances where the user does not care to withdraw the free end 19 of the belt from the buckle owing to the possibility of tearing said belt or otherwise marring its usual

highly polished surface. In such event, the belt is applied or removed from around the body by engaging or disengaging the hook portions 24 from the cross-bar.

It should be evident that transverse shifting of the hook portions 24 along the cross-bar 16 will result in misalignment of the overlapping end portions of the belt and thus detract from its otherwise attractive appearance. Such undesired transverse shifting is prevented in the instant device by suitably recessing the cross-bar 16 circumferentially, as at 25, said recesses being spaced and of sufficient width to coincide with the spacing and width of the hook portions 24. The recess 25 obviously define opposed pairs of shoulders 26 on the cross-bar 16, which shoulders provide abutting surfaces for the respective edges of the hook portion 22, thereby retaining the hook element in its required position to maintain the overlapping belt ends in alignment. The hook element 23 also may be made of plastics, shaped bone, wood, fiber or other form retaining material.

The plastic buckle disclosed in Figs. 5 to 7, inclusive, is substantially like that previously described except that in this instance the cross-bar 27, having an integral tongue 28, is rotatably mounted in the buckle frame so that the tongue 28 may be swung into and out of the plane of the buckle frame during the threading of the free end of the associated belt therethrough. As shown, the cross-bar 27 is circumferentially recessed at 25 to define spaced apart pairs of opposed shoulders 26 for receiving and preventing transverse shifting of the associated hook element 23 on the other belt end 22.

As best illustrated in Figs. 6 and 7, the end portions of the cross-bar 27 are of reduced diameter to provide bearings 29, which when assembled with the frame end, seat in suitable journals 31 provided on the rear face of the connecting frame portions 13a and 14a. The journals 31 are open on one side, as at 32, so that they may readily be spread during assembly. Such spreading is effected by flexing the connecting frame portions 13a and 14a sufficiently to widen the opening 32 to admit the bearing portions 29, as shown in Fig. 7. Immediately upon being released, the journals 31 return to their normal position shown in Fig. 6, and unintentional removal of the cross-bar is prevented.

Although exemplary forms of the improved buckle have been described herein and illustrated in the accompanying drawing in detail, it should

be evident that the invention may embody certain modifications to the extent that the overall shape of the buckle may vary in design or contour, that it may be made flat instead of bowed, and that the tongue may be formed integral with the cross-bar, irrespective of whether the latter is rotatable or rigid, without departing from the spirit of the invention and the scope of the appended claims.

10 I claim:

1. A buckle comprising a frame having transverse end portions and connecting side portions defining an opening, a transverse bar integral with the side portions and bisecting said opening, a tongue integral with said bar, said tongue being located substantially midway between the ends of said bar and having its free end located in spaced overlapping relation to one frame end portion, a notch in said frame end portion underlying said free tongue end, and shoulders on said bar, said shoulders being disposed on opposite sides of the tongue and providing an abutment for the edges of hook portions of an associate member when the latter is engaged over the bar between said shoulders.

2. A buckle comprising a frame having transverse end portions and connecting side portions defining an opening, a bar within said frame and bisecting said opening, a tongue integral with said bar adapted to extend through a hole in a belt when one end of the latter is threaded through said frame opening, said tongue being located substantially midway between the ends of said bar and having its free end in spaced overlapping relation to one frame end portion, a notch in the said end portion underlying said free tongue end, and recesses in said bar one on each side of and spaced from the tongue, said recesses each defining a pair of opposed shoulders adapted for abutment by the edges of hook portions carried on the other end of said belt and engaged over the bar in said recesses.

3. A buckle comprising a frame having an opening, a bar integral with the frame and bisecting said opening, a tongue integral with said bar adapted to extend through a hole in a belt when one end of the latter is threaded through said frame, recesses in said bar one on each side of and closely adjacent to the tongue, said recesses each defining a pair of opposed shoulders adapted for abutment by the edges of hook portions carried on the other end of said belt and engaged over the bar in said recesses.

RUDOLPH E. SCHREIBER.
